UNITED STATES PATENT OFFICE.

MERRITT R. HANSEN AND ALFRED C. HOUSER, OF COLUMBUS, OHIO, ASSIGNEES TO THE
BUCKEYE STEEL CASTINGS COMPANY, OF COLUMBUS, OHIO.

AIR-OPERATED CLAMPING DEVICE.

1,274,036.

Specification of Letters Patent. Patented July 30, 1918.

Application filed April 13, 1918. Serial No. 228,403.

To all whom it may concern:

Be it known that we, MERRITT R. HANSEN and ALFRED C. HOUSER, citizens of the United States, and residents of Columbus, 5 in the county of Franklin and State of Ohio, have invented certain new and useful Improvements in Air-Operated Clamping Devices; and we do hereby declare the following to be a full, clear, and exact description of the invention, such as will enable others skilled in the art to which it appertains to make and use the same.

This invention relates to air operated clamping devices designed more particularly 10 for use with molding apparatus.

The object of our invention is to provide a machine of the above type with a clamping device by which the machine operator through manipulating a conveniently located air valve, may quickly clamp the core plate to the core box, or the bottom board to the flask, and again release same after the core box or the flask has been placed in an inverted position, ready for the subsequent 15 separation of the core from the core box, or the mold from the pattern.

Another object of our invention is to provide a construction of clamps by which the parts at all times are under the operator's 20 control and so arranged that they will be clear to all other working parts of the machine.

With the above and other objects in view, our invention consists in the parts and combination of parts which will be more fully 25 pointed out and described in the claims.

While we have shown the application of our invention to one form of molding machine, we have done so for the purpose of 30 illustration only, and not with the intention of limiting our invention to such, or any other particular construction of molding machine.

In the accompanying drawings; Figure 1 35 is a view in side elevation showing our improved clamp applied to a "roll over" type of molding apparatus; Fig. 2 is a similar view, showing the carrier after it has been turned to its other position; Fig. 3 is a 40 view of the clamp; Fig. 3^a is a view in plan of the clamp; Fig. 4 is a view similar to Fig. 1 showing a modified form of clamp and Fig. 5 is a detached view of a part of the clamp.

55 Referring to the accompanying drawings,

6 represents a four way air valve, by means of which compressed air may be admitted at either side of the piston in the cylinder 7, and simultaneously exhausted at the opposite side of the same, thereby forcing an instantaneou 60 upward or downward movement of the piston rod 8. The piston rod is pivotally connected to the lever 9, which is fulcrumed to the swinging links 10, the latter being pivotally connected to a lug cast integral with the cylinder 7.

The cylinder 7 and the core box 11 are both secured to the roll over arm or carrier 12.

The lever 9 constitutes the clamp, and is 70 preferably in the form of a bell crank, with its fulcrum on the swinging link 10, at the angles of the two arms. One arm of the bell crank is pivotally connected to the outer free end of the piston rod 8, and the other arm 75 terminates in the bifurcated or U-shaped member 16 which constitutes the clamp proper.

In the operation of molding after ramming up the core box, the core plate 13 is 80 deposited on top of same.

By means of the four-way valve 6, compressed air is admitted on the lower side of the piston at 6°, and simultaneously exhausted through the upper outlet of the cylinder. 85 Hence the piston rod 8 will move instantly upward, thereby actuating the clamping lever 9 which operates to firmly clamp the core plate 13 against the top of the core box 11.

By manipulating the roll over arm or carrier 12 in the usual manner the core box and the cylinder will be transferred and inverted to the position shown in Fig. 2, and by thus reversing the four-way valve 6, air 95 will be admitted at 6° and exhausted through the pipe 6^a at the upper side of the cylinder, thus forcing the piston rod 8 upwardly and causing the lever 9 to withdraw to the position shown in Fig. 2, leaving a clear space 100 below for the subsequent removal of the core plate 13.

In Figs. 4 and 5 we have shown a modified form of clamping lever, whereby the piston rod 8^a is provided with a hook 8^b, embracing an extended lever arm 15, which latter is fulcrumed at its other extremity to a bracket 17 secured to the roll over arms. 105 With this construction when the air pressure is applied to the upper side of the piston 14 110

the core plate will be firmly clamped against the core box, and when the pressure is transferred to the other side of the piston, the lever arm 15 will be released.

- 5 It is evident that many slight variations might be resorted to in the relative arrangement of parts shown without departing from the spirit and scope of our invention, hence we would have it understood that we
10 do not wish to confine ourselves to the exact construction and arrangement of parts shown and described.

Having fully described our invention what we claim as new and desire to secure by Letters-Patent, is:—

1. In molding apparatus, the combination of a turn over support for a core box or flask, a cylinder movable with said support and having a piston, a clamp actuated by
20 the piston for clamping a plate or board to the box or flask, pipe connections with the cylinder at both sides of the piston and a valve for regulating the admission and exhaust of pressure medium to the cylinder.
25 2. In molding apparatus, the combination of a turn over support for a core box or flask, a cylinder carried by said support, pipe connections with the opposite ends of said cylinder, a four way valve for regulating the supply and discharge to said cylinder, a piston and piston rod, a clamp having pivotal connection with the piston rod and a rocking support for the clamp.
30 3. In molding apparatus, the combination of a turn over support, a cylinder secured
35

thereto, a piston in said cylinder, pipe connections with both ends of the cylinder, a four way valve included in said pipe connections and a clamp having connection with the piston rod.

4. The combination of a cylinder and piston and piston rod, pipe connections with both ends of the cylinder, a four way valve included in said pipe connections, a swinging link and a clamp pivoted to the piston rod 45 and also to the swinging link.

5. The combination of a cylinder, a piston and piston rod, pipe connections with both ends of the cylinder, a four way valve included in said pipe connections, a swinging link having its pivot fixed with relation to the cylinder, and a clamp having pivotal connection with the piston rod and also with the swinging link.

6. The combination of a cylinder, a piston and piston rod, pipes for supplying pressure medium to and for exhausting it from said cylinder, a four way valve included in said pipe connection, a swinging link pivoted to a lug on the cylinder and a 55 clamp having pivotal connection with said link and also with the piston rod.

In testimony whereof, we have signed this specification in the presence of two subscribing witnesses.

MERRITT R. HANSEN.
ALFRED C. Houser.
